UNITED STATES PATENT OFFICE.

REINHOLD A. NORLING, OF AURORA, ILLINOIS, ASSIGNOR TO AURORA AUTOMATIC MACHINERY COMPANY, OF AURORA, ILLINOIS, A CORPORATION OF ILLINOIS.

THROTTLE-VALVE FOR PORTABLE PNEUMATIC MOTORS.

SPECIFICATION forming part of Letters Patent No. 762,933, dated June 21, 1904.

Application filed November 19, 1903. Serial No. 181,804. (No model.)

To all whom it may concern:

Be it known that I, REINHOLD A. NORLING, a citizen of the United States, and a resident of Aurora, in the county of Kane and State of Illinois, have invented certain new and useful Improvements in Throttle-Valves for Portable Pneumatic Motors; and I do hereby declare that the following is a full, clear, and exact description thereof, reference being had to the accompanying drawings, and to the letters of reference marked thereon, which form a part of this specification.

This invention relates to improvements in throttle-valves for pneumatic drills or mechanisms of that kind embracing a fluid-pressure engine of portable form applied to operate a drill or like tool.

The invention consists in the matters hereinafter described, and pointed out in the appended claims.

In the accompanying drawings, Figure 1 is a side view of a part of the casing of a pneumatic drill with the throttle-valve attached thereto. Fig. 2 is a view in central longitudinal section of the throttle-valve. Fig. 3 is a cross-section taken on line 3 3 of Fig. 2. Fig. 4 is a cross-section taken on line 4 4 of Fig. 2.

As shown in said drawings, A indicates a part of the casing of a portable pneumatic motor, and B a supply-pipe through which compressed air or other fluid is supplied to the motor. Said air-supply tube is attached rigidly to and projects from the casing of the motor and will usually constitute one of the handles of the motor. In said air-supply pipe B is formed the throttle-valve, which is operated through the medium of a tubular rotative handle or grip C, mounted on and surrounding said air-supply pipe.

As shown in the accompanying drawings, the air-pipe B is connected with the side of the casing A by means of a plug D. The plug D has an intermediate flat-sided part for the application of a wrench, a projection or nipple which enters the wall of the casing A, and at its outer end a screw-threaded portion which enters and is engaged by the pipe B. The

part B' of the pipe B is reduced in diameter, and around the same is placed the rotative tubular handle or sleeve C, which is grasped by the hand of the operator using the machine and which may be turned upon the pipe B. The tubular handle or sleeve C is shown as held in place on the tube B by means of a screw-threaded ring b, applied to the screw-threaded outer end of said pipe B. The outer end of the plug D, which enters the pipe B, forms a valve-seat and is provided with two ports or openings d d, which extend obliquely to the central opening d' of said plug, that leads into the air-chamber A' of the casing. The said ports d d open through the flat outer face or valve-seat on the plug, and in contact with said flat outer face is a rotative valve-disk E, which is provided with two ports e e, which correspond in position with the ports d d. Each of the ports d d in the valve-seat and of the ports e e in the rotative valve-disk is located eccentrically to or at one side of the axis of rotation of the valve-disk, so that by the turning of the disk the ports in the seat may be closed or wholly or partially opened. The said rotative valve-disk E has two lugs e' e', in which are formed transverse slots e' e'. Said lugs e' e' are separated, so as to form between them a space or recess adapted to receive the cylindric stem f on a rotative valve-actuating plug F, which is mounted to turn within the pipe B and is connected with the handle C. The stem f is provided with a cross-pin f', which engages at its ends the transverse slots formed in the lugs e' e'. Said plug F is shown as immediately engaging a thimble G, which is inserted and secured in the smaller part B' of the pipe B and which forms a bearing in which the plug rotates. Said plug is connected with the sleeve C by means of a radial stud c, which passes through a curved slot b, formed in the pipe B, and a like slot g, formed in the thimble G. The rotative plug F is provided with a longitudinal groove F', forming a passage for air from the main part of the air-inlet pipe past the said plug to the valve formed by the valve-disk E.

It will be manifest that when the plug F is turned by rotation of the sleeve C it will by reason of being connected with the valve-plate E by the connections described correspondingly turn said valve-plate, and thus wholly or partially cut off the air-supply, as desired. It will be observed that the valve-plate E, being loosely connected with the plug F by the pin f and slotted lugs e', is free to move toward and from the valve-seat formed on the outer end of the plug D and will be held by the air-pressure against said valve-seat, thereby preventing leakage of air when the valve is closed.

15 I claim as my invention—

1. The combination with a supply-pipe, of a rotative throttle-valve embracing an endwise-facing valve-seat provided with a port, a rotative valve-disk which rests in contact with and is adapted to turn on said valve-seat and is also provided with a port, and a rotative tubular handle on the supply-pipe which is connected with and adapted to give rotative movement to said valve-disk, the ports in the valve seat and disk being arranged eccentrically to the axis of rotation of said disk.
2. The combination with a supply-pipe, of a rotative throttle-valve, said throttle-valve embracing an endwise-facing valve-seat, a rotative valve-disk resting thereon, and means for operating said valve-disk from the exterior of the supply-pipe, said valve-operating means being loosely connected with said valve-disk

so that the pressure in the supply-pipe tends to hold the disk against its said seat.

35

3. The combination with a supply-pipe, of a rotative throttle-valve embracing an endwise-facing valve-seat, a rotative valve-disk resting against said seat, a rotatable sleeve or tubular handle mounted on said supply-pipe, and operative connections between the said tubular handle and the valve-disk which are loosely connected with the valve-disk, so as to permit the pressure in the pipe to hold the disk against its seat.

40

4. The combination with a supply-pipe, of a rotative throttle-valve, said valve embracing an endwise-facing valve-seat, a valve-disk adapted to rest against said valve-seat, a rotative sleeve or tubular handle mounted on said supply-pipe, a rotative plug mounted to turn in the supply-pipe and connected with said tubular handle, said plug having a longitudinal passage to permit the passage of air past the same and being connected with the valve-disk by a loose joint affording endwise movement of the valve-disk with respect to the plug.

45

In testimony that I claim the foregoing as my invention I affix my signature, in presence of two witnesses, this 16th day of November, 60
A. D. 1903.

REINHOLD A. NORLING.
